UNITED STATES PATENT OFFICE.

PAUL H. ZIMMER, OF MILWAUKEE, WISCONSIN, ASSIGNEE TO THE CUTLER-HAMMER MFG. CO., OF MILWAUKEE, WISCONSIN, A CORPORATION OF WISCONSIN.

ELECTRIC SWITCH.

1,221,499.

Specification of Letters Patent.

Patented Apr. 3, 1917.

Application filed November 6, 1911. Serial No. 658,862.

To all whom it may concern:

Be it known that I, PAUL H. ZIMMER, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

10 My invention relates to improvements in electric switches.

15 My invention is particularly applicable to circuit breakers including an electro-magnetically set switch and means for causing the opening of said switch upon the occurrence of abnormal conditions in the circuit controlled thereby. My invention, however, is not limited in its application to such devices.

20 For the purpose of disclosing the nature, characteristic features and advantages of my invention I shall describe the device illustrated in the accompanying drawings which embodies my invention in one form. 25 It should be understood, however, that my invention is not limited to the specific embodiment thereof selected for the purpose of illustration but is susceptible of embodiment in various other forms.

30 In the accompanying drawings:—

Figure 1 is the front elevation of the device.

Fig. 2 is the vertical sectional view taken 35 on line 2—2 Fig. 1.

Fig. 3 is a perspective view of one of the switch arms.

Fig. 4 is a diagrammatic view showing the device used as a circuit breaker.

40 Briefly described the device selected for the purpose of illustration comprises a solenoid-operated switch with a releasable connection between the switch and the plunger of its operating solenoid and an overload 45 device adapted to break said connection to allow the switch to open while the solenoid remains energized.

The several parts of the device are mounted upon an insulating supporting panel 1. 50 The switch is shown as being provided with arms 2 and 3. These arms are mounted upon a cross member 4 fulcrumed at opposite ends in suitable bearings 6 and 7 suitably secured to the panel 1. The arms may 55 be mounted upon this cross member in any

suitable manner but in practice I prefer to mount them as illustrated. Both arms are mounted in the same manner and therefore the description of one will suffice for both. As is best illustrated in Fig. 3 the arm 2 is 60 mounted upon an upwardly projecting lug 8 on the cross member 4. This lug carries an outwardly projecting pin 9 which passes through the arm 2 and which has on its outer end a coil spring 10 confined between 65 the outer face of the arm 2 and a collar 11 on the extremity of said pin. This provides a yielding connection between the arm and the cross member. For preventing rotary movement of the arm 2 about the pin 9, the 70 lower extremity of said arm is confined between lugs 12 and 13 provided upon the cross member 4. The arms 2 and 3 are provided at their upper extremities with contacts 2^a and 3^a respectively, adapted to engage contacts 2^b and 3^b respectively, mounted upon the panel 1.

The aforesaid switch arms are adapted to be actuated by a solenoid 14 mounted in a suitable frame 15 secured to the panel 1 between the switch arms. This solenoid is provided with a reciprocating plunger 16.

The connection between the switch arms and the solenoid plunger is as follows: The plunger is provided at its lower end with a 85 bifurcated extension 17 within which is pivoted a hook member 18, said member being pivoted upon a pin 19 passing through the bifurcated portions of the member 17. The hook member is adapted to hook upon a 90 roller 20 carried between forwardly projecting lugs 21 and 22 on the cross member 4 supporting the switch arms. This roller is revolvably mounted upon a pin 23 passing through said projections 21 and 22. The 95 hook member 18 is biased in a direction to hook upon the roller 20 by a tension spring 24 connected at one end to a pin 25 projecting from the solenoid plunger and at its opposite end to an extension 26 on the hook 100 member.

The connection between the solenoid plunger and switch thus provided is such that the two may be readily connected or disconnected by shifting of the hook member 18 upon its pivot. Thus assuming that the solenoid plunger and switch have been connected, and the solenoid energized the switch may be readily released by moving the hook to disengage the roller 20 and this 110

without deenergization of the solenoid 14. The switch would then move to open position due to gravity and the influence of the springs 10. Assuming now that the solenoid 5 be deenergized its plunger would drop causing the extremity of the hook member to strike the upper side of the roller 20. As illustrated the extremity of the hook member is slightly curved so that the weight of 10 the plunger would cause the hook member to shunt off of and pass the roller 20 after which the spring 24 would return the hook member to normal position thus throwing the extremity thereof under the roller. 15 Thus, upon deenergization of the solenoid its plunger would be automatically relocked to the switch members. The switch would then be in condition for further operation.

An overload device 28 is provided for actuating the hook member to release the switch from the solenoid plunger. This device may be conveniently mounted upon the front of the magnet frame 15 as illustrated. It comprises a magnet M having pole pieces 20 25 29 and 30 and an armature 31. The armature 31 is fulcrumed to the pole piece 30 and is provided with an extension 32 projecting into proximity with a lug 33 on the hook member 18. The arrangement is such 30 that when the solenoid 14 is energized and the magnet M attracts its armature the extension 32 of the armature strikes the lug 33 disengaging the hook member from the roller 20 with the results above described. 35 Mounted upon the front of the overload device is a curved calibrating plate 34 having at its lower end a projection 35 carrying a set screw 36 for limiting the downward movement of the armature 31 of the 40 overload device. The adjustment of the screw 36 affords a simple means of calibrating the overload device to respond under the desired conditions.

In the diagrammatic view, Fig. 4, I have 45 for the purpose of simplifying the same merely shown the switch as provided with one contact arm it being understood that the device may be provided with either one of a plurality of arms as desired. The device is illustrated as used for connecting a translating circuit 37, 38, to a power circuit L—L'. The switch is adapted to be set by closure of a normally open push button 39. This completes a circuit from power 50 line L through said push button by conductor 40 through the solenoid winding 14 by conductor 41 to power line L'. This completes the connection of the line 37 of the translating circuit to the power circuit 55 through the overload magnet M and through the switch arm 2 to the line L, the line 37 of the translating circuit being permanently connected to the line L'. Immediately upon this circuit being closed a circuit is 60 established from power line L through

switch 2 by conductor 42 through a protecting resistance R and a normally closed push button 43 to conductor 40 and thence through the solenoid winding 14, as already traced. The push button 39 may now be released without interrupting the circuit of 70 the solenoid 14.

Assuming now that the overload magnet M responds and releases the switch arm 2 from the plunger of the solenoid 14 in the 75 manner previously set forth, the switch arm would immediately open disconnecting the translating circuit from the power circuit. It would also interrupt the maintaining circuit of the solenoid winding 14 causing said 80 winding to be deenergized. The solenoid would then drop its plunger which upon its descent would be automatically relocked with the arm 2 in the manner previously set forth.

The switch 2 may be opened at will by pressing the push button 43 thereby interrupting its maintaining circuit.

It will thus be seen that the device is admirably suited for circuit breaker service. 90 It obviates the necessity for using the overload device for making or breaking circuit and further obviates the necessity of any special provision to prevent automatic resetting of the solenoid switch upon return 95 of the overload device to normal position.

What I claim as new and desire to secure by Letters Patent is as follows:—

1. In combination, an oscillatable bar, an operating arm and a switch contact arm 100 carried thereby for movement therewith, a solenoid having a plunger terminating adjacent said operating arm for actuating the latter, a hook carried by said plunger for normally maintaining direct mechanical 105 connection with said operating arm, and electro-responsive means for interrupting said connection under predetermined electrical conditions.

2. In combination, a switch contact arm 110 and an operating arm mounted for joint oscillation, a solenoid for actuating the same, means carried by the solenoid plunger for directly connecting the same with said operating arm, and means for automatically 115 interrupting said connection under predetermined conditions.

3. In combination, a switch contact arm, an operating arm therefor mounted for joint oscillation therewith, a solenoid for actuating said arm, releasable means carried by the plunger of said solenoid and biased to maintain direct operative connection with said operating arm, and electro-responsive means for tripping said connecting means 120 under predetermined electrical conditions during energization of said solenoid.

4. In a circuit breaker, in combination, a switch arm and an operating arm mounted for joint oscillation, a solenoid, means car- 125 130

ried by the plunger of said solenoid for normally maintaining a direct connection with said operating arm for actuating the latter, an overload magnet for tripping said connecting means; and controlling means for said solenoid operable to close said switch at will but insuring against automatic reclosure after the same has been tripped.

5. In combination, a vertically disposed supporting base, a switch operating arm pivotally mounted thereon, a solenoid mounted on said base above the pivotal point of said member, a direct operative connection between the plunger of said solenoid and said member comprising a catch on one biased to engage a shoulder on the other, an overload magnet having an

armature member constituting means to trip said catch while said solenoid is energized, and adjustable means for calibrating the response of said armature member, said adjustable means, said armature member and said operative connection between the plunger of said solenoid and said switch being disposed perpendicularly with respect to said base and all accessible from below said solenoid and said magnet.

In witness whereof, I have hereunto subscribed my name in the presence of two witnesses.

PAUL H. ZIMMER.
